UNITED STATES PATENT OFFICE

2,249,463

SUCTION NOZZLE

Ralph E. Dunbar, East Cleveland, Ohio, assignor
to Electric Vacuum Cleaner Company, Inc.,
Cleveland, Ohio, a corporation of New York

Application July 21, 1939, Serial No. 285,709

1 Claim. (Cl. 15—158)

The present invention relates to suction nozzles for use with vacuum cleaners of the type having a flexible hose connecting the suction nozzle and the suction producing means.

The object of my invention is to provide an improved construction and arrangement in suction nozzles of this type, and for a consideration of what I believe novel and my invention, attention is directed to the following description and the claim appended thereto.

In the accompanying drawing Fig. 1 is a perspective view of a suction nozzle embodying my invention; Fig. 2 is a side elevation; Fig. 3 is a rear elevation; and Fig. 4 is a perspective view of the bottom of the nozzle.

Referring to the drawing, there is shown a suction nozzle 1 having front and rear surface contacting lips 2 and 3. As shown in Fig. 3, the ends of the nozzle lips are lower than the intermediate portions. Accordingly the intermediate portions of the nozzle lips are supported slightly above the surface being cleaned. If the nozzle is used for cleaning a floor covering, the floor covering will therefore be raised from the floor against the intermediate portions of the nozzle lips and will be subjected to a flexing action as the nozzle is moved across the floor covering.

On the rear side of the nozzle is a downwardly facing recess defined by end walls 4 and top and rear walls 5 integral with the nozzle. The recess extends only along the intermediate part of the nozzle. In the recess is a brush 6 mounted in the manner shown in my application Serial No. 164,369, filed September 17, 1937, now Patent 2,205,877. As disclosed in this application, the vertical position of the brush is adjusted by a screw 7 extending through a cam slot 8 in the wall 5. At the ends of the suction nozzle are arcuate shoes 9 extending rearwardly and upwardly from the rear nozzle lips 3. The shoes are integral with the rear nozzle lips and the end walls 4, and from one aspect constitute a fillet between the rear nozzle lips and the ends of the recess. As shown in Fig. 2, the lower end of the brush is above the plane of the shoes adjacent the rear nozzle lip and below the plane of the rear ends of the shoes. Accordingly, when the nozzle is rocked or tilted on the shoes the brush is brought into engagement with the floor covering. At the same time the front and rear nozzle lips are raised to permit a greater admission of air between the floor covering and the nozzle lips which will entrain the dirt removed from the floor covering by the agitation of the

brush 6. The shoes 9 being in contact with the floor covering restrict the air flow to the suction nozzle to the section adjacent the brush. This increases the effectiveness of the cleaning. The shoes do not interfere with the action of the brush.

In use the suction nozzle is connected by a swivel coupling 10 to a tube 11 telescoped within a rigid suction tube 12 which is connected at its upper end to a flexible hose 13. The suction tube 12 is made in telescoping sections so that the length is adjustable. It serves as a handle by means of which the nozzle may be moved over the surface being cleaned. Under normal conditions the nozzle is supported on the floor covering by the nozzle lips 2 and 3 and the shoes 9 are slightly above the floor covering. In this condition the brush either bears lightly on or is slightly above the surface of the floor covering. This is the condition most effective for normal cleaning. If an exceptionally dirty spot is encountered the suction tube 12 is lowered, rocking the nozzle on the shoes 9 and bringing the brush into engagement with the floor covering. This subjects the floor covering to a scrubbing action, and the dirt loosened by this action is more easily drawn into the suction nozzle due to the large air flow caused by the raising of the front and rear nozzle lips. During normal cleaning the front ends of the shoes contact the floor covering, and in deep pile carpets the nozzle lips may sink into the pile of the carpet so that the nozzle will be partially supported on the arcuate surfaces of the shoes. This makes the nozzle somewhat easier to push.

What I claim as new and desire to secure by Letters Patent of the United States is:

In a vacuum cleaner, a suction nozzle having front and rear surface engaging lips and provisions for connection with a suction tube which serves as a handle for moving the nozzle over the surface being cleaned, shoes at the ends of the nozzle inclined rearwardly and upwardly from the rear nozzle lip, and a brush extending along the nozzle at the rear of the rear nozzle lip opposite the intermediate portions of the shoes and in front of the rear ends of the shoes, said brush projecting below the plane of said intermediate portions of the shoes but not to the plane of the front ends of the shoes whereby the brush engages the surface being cleaned when the nozzle is tilted rearwardly on said shoes to raise the nozzle lips.

RALPH E. DUNBAR.
